CLAIM

The ornamental design for a surface downlight, as shown and described.

DESCRIPTION

FIG. 1 is a perspective view of a surface downlight, showing our new design;

FIG. 2 is a bottom plan view thereof;

FIG. 3 is a top plan view thereof;

FIG. 4 is a front elevation view thereof;

FIG. 5 is a back elevation view thereof;

FIG. 6 is a left-side elevation view thereof; and,

FIG. 7 is a right-side elevation view thereof.

The broken lines shown represent portions of a surface downlight which form no part of the claimed design.
